UNITED STATES PATENT OFFICE

ROBERT L. LYONS, OF WALTHAM, MASSACHUSETTS.

DESIGN FOR A THROAT-PLATE FOR SEWING-MACHINES.

SPECIFICATION forming part of Design No. 35,487, dated December 24, 1901.

Application filed November 16, 1901. Serial No. 82,603. Term of patent 7 years.

To all whom it may concern:

Be it known that I, ROBERT L. LYONS, a citizen of the United States, residing at Waltham, in the county of Middlesex and State 5 of Massachusetts, have invented and produced a certain new, useful, and original Design for a Throat-Plate for Sewing-Machines, of which the following is a specification, reference being had therein to the accompanying drawings.

This invention relates to a new and original design for a throat-plate for sewing-machines.

Figure 1 represents a plan view of a throat- 15 plate for sewing-machines, illustrating my new design. Fig. 2 represents an obverse view thereof in perspective to more clearly show the design. Fig. 3 represents a cross-sectional view thereof, taken on line 3 3, Fig. 20 1. Fig. 4 represents a cross-sectional view of the same, taken on line 4 4, Fig. 1.

The leading feature of my new design for a throat-plate for sewing-machines consists in the design of the plate as herein shown and described.

As shown in the drawings, the plate 5 has the centrally-disposed opening 6, from which the slot 7 extends toward the end 5' of the plate 5. The edges 8 and 9 of the slot 7 tend toward each other until they meet at the point 30 10, the edge 8 being square with the surface of the plate, while the edge 9 is beveled on its obverse, as shown.

What I claim is—

The design for a throat-plate for sewing- 35 machines as herein shown and described.

In testimony whereof I affix my signature in presence of two witnesses.

ROBERT L. LYONS.

Witnesses:

CHARLES W. HODGDON,
H. J. MILLER.
